Inventor:

Robert Munro
By his Atty.,

Alphonso B. Smith

UNITED STATES PATENT OFFICE.

REUBEN MUNRO, OF SAN FRANCISCO, CALIFORNIA.

CAR-AXLE LUBRICATOR.

SPECIFICATION forming part of Letters Patent No. 320,382, dated June 16, 1885.

Application filed September 23, 1884. (No model.)

To all whom it may concern:

Be it known that I, REUBEN MUNRO, a citizen of the United States, residing in the city and county of San Francisco, and State of California, have invented certain new and useful Improvements in Journal-Lubricators for Railway-Axes; and I do hereby declare that the following is a full, clear, and exact description of my said invention and of the manner in which I proceed to construct, produce, and apply the same, reference being had to the drawings that accompany and form part of this specification.

My invention relates to a lubricating device for railway-axes; and it consists in certain usual construction of parts and their application and combination within a car-axle box, producing a lubricant of improved operation and great simplicity, cheapness of manufacture, and durability.

In the accompanying drawings, referred to by figures and letters, Figure 1 is a longitudinal section taken vertically through an axle-box and the parts of my device applied to it. Fig. 2 is a section, also vertical, taken transversely. Fig. 3 is a detail view.

The axle-box B is of any construction now in use wherein the space or chamber below the journal is of sufficient size to admit the parts of my device. These parts consist of a tray or plate, A, with a perforated surface set on spring-legs beneath the journal and a body of some absorbing material or substance—as cotton-waste or sponge—which, being laid upon the plate or yielding surface, is held up against the under surface of the journal. The plate A has a number of holes or perforations, a a, through which the oil or lubricant contained in the lower part of the axle-box chamber reaches the absorbent material C, and the edges of the plate are turned up around the four sides to form a rim for confining this material. The spring-legs d d are flat plate or leaf springs.

The improved construction is to take two metal springs and fix them by one end to the opposite sides of the tray or plate in such manner that they can be bent under the tray and from opposite directions to cross or extend past each other underneath the middle of the tray. This number could be increased, if necessary, by adding one or two spring-legs

in the same manner. The bottom of the axle-box B is provided with ledges or projections b b, lying on each side of the springs d d, as shown in Fig. 1, and serving to keep the springs d d, with their attached plate A, under the spindle. Upon this spring-supported surface I place a body of some soft absorbent material or substance as the vehicle for applying the oil or lubricant. Tow, cotton, or prepared sponge will answer for this purpose. A body of it is laid on the tray in sufficient quantity to cover the length of the journal, and in such mass or body as will fill up the space above the tray and afford required contact with the journal. While thus supplied and held to the place this material is constantly receiving and taking up a supply from the lubricant in the chamber beneath it through the splash and disturbance of the liquid, while it is not submerged or immersed, but is held up out of the liquid. The condition of the lubricant and the quantity on hand in the chamber can be ascertained, therefore, at any time by raising the lid or cover of the box, and thus the liquid can be replenished when needed without waste or extravagant use. The construction likewise affords a ready and inexpensive renewing of the lubricating medium when required.

Having thus fully described my invention, what I claim, and desire to secure by Letters Patent, is—

1. The combination, with the car-axle, absorbent material C, and perforated plate A, of the springs d d, formed of strap-pieces secured at the ends of the plate A and bent into an inclined position, as shown, so that the springs from the two ends of the plate cross each other and rest upon the box under the opposite ends of said plate.

2. The combination, with the car-axle, absorbent material C, plate A, and springs d d, of the box B, having the ledges or projections b b on the bottom thereof, as and for the purpose set forth.

In witness that I claim the foregoing I have hereunto set my hand and seal.

REUBEN MUNRO. [L. S.]
